CROWN CAP

George H. Hutaff, Jr., Wilmington, N. C.

Application December 23, 1935, Serial No. 55,887

7 Claims. (CL. 215—46)

This invention relates to crown caps for bottles and like containers and has for an object to provide a crown cap having a crimped flange which may be severed along an oblique line of indentations extending from a point where the flange engages underneath the beading on the neck of the bottle to a point substantially above where the flange disengages from underneath the beading whereby to produce a tapered strip which may be manually pulled upwardly to easily and quickly remove the cap from the bottle.

A further object is to provide a crown cap having a frangible portion providing a tapered strip for manually removing the cap from the bottle neck without the use of tools, the frangible portion lying wholly within the contour of the crown cap so that the cap may be used in all bottling machines without alterations to the machines and will not interfere with application of the caps to the bottles at high speeds.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part 30 of this specification,

Figure 1 is a front elevation of a bottle neck showing a crown cap constructed in accordance with the invention applied thereto.

Figure 2 is a perspective view of the parts shown in Figure 1, with the flange of the cap partly ripped away providing a tapered strip by means of which the cap may be jerked from the bottle.

Figure 3 is an enlarged detail sectional view taken on the line 3—3 of Figure 1.

Figure 4 is a front elevation of a modified form of the invention, in applied position.

Referring now to the drawing in which like characters of reference designate similar parts in the various views, the reference numeral 10 indicates a cap for sealing a bottle or like container 11, the cap being of the crown type and including a disc 12 and a crimped flange 13, the same preferably being formed of sheet aluminum of sufficient rigidity to withstand pressure of carbonated and uncarbonated beverages and the like while at the same time being sufficiently frangible to permit being readily torn or ripped manually by the fingers without the use of tools such as the conventional bottle cap remover.

The cap is provided on the underneath side with a gasket 14 which is confined against the beading 15 on the neck of the bottle by means 60 of the crimps of the flange engaging underneath

the beading. The gasket seals the bottle pressure and leak tight.

In carrying out the invention a line 16 of indentations is formed in the flange extending circumferentially and obliquely upward from a point 17 where the flange 13 engages underneath the beading 15 on the neck of the bottle to a point 18 substantially above where the flange disengages from underneath the beading, as shown in Figure 2 and Figure 3. Thus the line of indentations provides a weakened portion of the flange extending obliquely upward and progressing from a point underneath the beading at its low end to a point at its upper end where it may be said the flange disengages from underneath the bead- 15 ing entirely.

A cut 19 of rectilinear or triangular contour is formed in the flange and extends from the edge of the flange to the low end of the line of indentations. This cut provides a notch within which 20 the operator may insert his thumb nail underneath the flange to start a tear or rip along the line of indentations, and the severed portion may be gripped by the fingers to rip the flange along the entire length of the line of indentations, as 25 best shown in Figure 2. The severed strip 20 tapers from the cut 17 to its wide end 21 at the high end of the line of indentations 16. This tapered strip provides a grip which may be forced transversely across the disc 12 of the cap to 30 jerk the cap from the bottle. Since the ripping operation along the line of indentations 16 has already partly removed the crimped flange along a considerable portion thereof from its engagement underneath the beading 15, a very slight 35 pull upon the tapered strip 20 will be sufficient to easily lift the cap from the bottle.

In Figure 4 there is shown a modified form of the invention in which the cap is identically the same as above described, and hence has been 40 given similar reference numerals with the single exception that the line of indentations 16 is continued beyond the cut 19, as shown at 22. The purpose of this is to permit an additional strip 23 to be ripped off the flange thereby dis- 45 engaging the crimped flange from underneath the beading along an arcuate distance substantially twice as great as the form of the invention shown in Figures 1 and 2.

By crown cap in the specification is meant 50 a bottle stopper composed of a sealing disc gasket and a metallic sealing cap encircling the periphery of the disc gasket and having a flange adapted to be bent into locking contact with the beading upon the neck of the bottle, the 55 flange being crimped to provide corrugations which afford circumferential resiliency.

From the above description it is thought that the construction and operation of the invention 60

will be fully understood without further explanation.

What is claimed is:

1. A crown cap for application to bottles and like containers by conventional bottling machines, including a sealing disc gasket, and a metallic sealing cap encircling the periphery of the disc gasket and having a flange adapted to be bent into locking contact with the beading upon the neck of the bottle, said flange being crimped or corrugated to afford circumferential resiliency, the crimped flange being provided with a line of indentations extending circumferentially and obliquely upward from a point where the flange engages underneath the beading on the neck of the bottle to a point substantially above where the flange disengages from underneath the beading, said flange having a cut extending from the free edge thereof upward to the low end of the line of indentations to permit the flange being ripped and severed along the oblique line of indentations, the ripping and severing operation producing a tapered strip by means of which the cap may be jerked from the bottle.
2. A crown cap for application to bottles and like containers by conventional bottling machines, including a sealing disc gasket, and a metallic sealing cap encircling the periphery of the disc gasket and having a flange adapted to be bent into locking contact with the beading on the neck of the bottle, said flange being crimped or corrugated to afford circumferential resiliency, the crimped flange being provided with lines of indentations extending in opposite directions circumferentially and obliquely upward from a common point where the flange engages underneath the beading on the neck of the bottle to points substantially above where the flange disengages from underneath the beading, said flange having a cut extending from the edge thereof upward to said common point at the low ends of the lines of indentations to permit the flange being ripped and severed along the oblique lines of indentations, the ripping and severing operation producing a plurality of spaced tapered strips by means of which the cap may be jerked from the bottle.
3. A closure for a bottle having a beaded neck, comprising a metal cap having a disc portion and an integral depending flange having downwardly and outwardly extending flutes adapted to be crimped underneath the beading of the bottle neck, and a fluted tongue adapted to be torn along the flange for an angular distance of a quadrant more or less circumferentially around the flange and defined by the edge of the flange and by a line of indentations passing obliquely across a plurality of contiguous flutes and terminating adjacent to the tip of the final flute embraced by the tongue, the indentations thus passing obliquely across the beading of the bottle neck, the tongue when severed along said indentations disengaging from underneath said beading and forming a long grip for dislodging the cap from the bottle neck.
4. A closure for a bottle having a beaded neck, comprising a metal cap having a disc portion and an integral depending flange having a portion provided with downwardly and outwardly extending flutes adapted to be crimped underneath the beading of the bottle neck, and a pair of circumferential lines of indentations extend-

ing in opposite directions from a common point on the fluted portion of the flange obliquely upward across the beading of the bottle neck and through a plurality of contiguous flutes, said line of indentations passing out of the fluted portion of the flange remote from said common point and permitting of a pair of tapered fluted tongues being severed along the edge of the flange from said common point circumferentially of the flange in opposite directions to form a pair of oppositely disposed long grips for dislodging the cap from the bottle neck.

5. A closure for a bottle having a beaded neck, comprising a metal cap having a disc portion and an integral depending flange having downwardly and outwardly extending flutes adapted to be crimped underneath the beading of the bottle neck, a circumferentially extending tapered tongue defined by a line of indentations extending circumferentially of the cap in the flutes and being disposed obliquely upward across the beading of the bottle neck and across the flutes from about midway of the ends of one of the flutes to above the final flute embraced by the tongue, and an inverted V-shaped opening formed in the edge of the flange and extending at the apex to the beginning of said line of indentations for admitting a tearing means to permit the fluted tongue to be severed along the line of indentations and dislodged from underneath the beading of the bottle neck for effecting removal of the cap.

6. A closure for a bottle having a beaded neck, comprising a metal cap having a disc portion and having a depending flange of uniform width throughout and provided with downwardly and outwardly extending flutes beginning at the lower edge of the flange and terminating at a point near the disc portion, and a tongue forming a fluted grip for dislodging the cap and extending circumferentially along the edge portion of said flange, said tongue including a plurality of the flutes for an angular distance of about a quadrant more or less of the circumference of the flange and being defined at the upper longitudinal edge by a frangible line of indentations in the flange extending from one of the flutes obliquely upwardly across the beading of the bottle neck and terminating above the final flute forming the tongue.

7. A crown cap for application to bottles and like containers by conventional bottling machines, including a sealing disc gasket, and a metallic sealing cap encircling the periphery of the disc gasket and having a flange adapted to be bent into locking contact with the beading upon the neck of the bottle, said flange being crimped or corrugated to afford circumferential resiliency, the crimped flange being provided with a line of indentations extending circumferentially and in part above the point where the flange disengages from underneath the beading, said flange having a cut extending from the free edge thereof upward to the adjacent end of the line of indentations to permit the flange being ripped and severed along the line of indentations, the ripping and severing operation producing a crimped strip by means of which the cap may be jerked from the bottle, the portion of the cap forming the strip being normally located not to project below the normal bottom edge of the cap.
